CHARLES H. THORNTON
TURRET RING
DESIGN

N° 3562

PATENTED
JUN 29 1869

Charles H. Thornton
Plympton & Co
Attest.

United States Patent Office.

CHARLES HENRY THORNTON, OF NEWARK, NEW JERSEY.

Design No. 3,562, dated June 29, 1869.

DESIGN FOR A TERRET-RING.

The Schedule referred to in these Letters Patent and making part of the same.

To all whom it may concern:

Be it known that I, CHARLES HENRY THORNTON, of Newark, in the county of Essex, and State of New Jersey, have originated and designed a new and improved Terret-Ring for harness, of which the following is a full, clear, and exact description, reference being had to the accompanying drawings, making part of this specification.

This invention relates to a new and elegant design for terret-rings for harness; and

It consists in forming the frame of the ring with a rounded or arched top, the sides sloping gradually inward toward the bottom, which is curvilinear, or in the shape of an inverted arch. This lower curve is of less radius than the upper, so that the ring thus con-

structed presents a unique and graceful appearance to the eye.

A terret-ring, constructed after my design, may be covered with leather, or lined, or not, as the taste of the purchaser may dictate, all of which is apparent from the drawing attached to and forming part of this specification, which clearly shows my design.

What I claim as my invention, and desire to secure by Letters Patent, is—

The design or pattern for terret-rings, as herein set forth and shown.

CHARLES HENRY THORNTON.
